UNITED STATES PATENT OFFICE

147,586

DESIGN FOR A COMBINED BOOK END AND NUTCRACKER

Arnold J. Hotz, Cleveland, Ohio

Application April 23, 1946, Serial No. 128,873

Term of patent 14 years

(Cl. D89—1)

To all whom it may concern:

Be it known that I, Arnold J. Hotz, a citizen of the United States, residing at Cleveland, in the county of Cuyahoga and State of Ohio, have invented a new, original, and ornamental Design for a Combined Book End and Nut Cracker, of which the following is a specification, reference being had to the accompanying drawing, forming part thereof.

In the drawing:

Figure 1 is a front perspective view of my design for a combined book end and nut cracker, and

I claim:

The ornamental design for a combined book end and nut cracker, as shown.

ARNOLD J. HOTZ.
